COMBINED MEDICINAL STEAM VAPORIZER AND HUMIDIFIER OR THE LIKE

Lawrence Katzman, 614 W. 49th St., New York, N.Y.

Filed Feb. 20, 1961, Ser. No. 64,001

Term of patent 14 years

(Cl. D83—1)

FIG.1

I claim:

The ornamental design for a combined medicinal steam vaporizer and humidifier or the like, as shown and described.
